UNITED STATES PATENT OFFICE.

LUMAN HOLDEN, OF MANCHESTER, NEW HAMPSHIRE, ASSIGNOR TO W. H. McELWAIN COMPANY, OF BOSTON, MASSACHUSETTS, A CORPORATION OF MASSACHUSETTS.

MACHINE FOR INSERTING FASTENINGS.

Application filed August 10, 1921. Serial No. 491,131.

This invention relates to fastener inserting machines, and more particularly to improvements in such machines for insuring an accurate spacing of the fasteners to suit the particular work being operated upon. The improvement may be adapted to all types of fastener inserting machines, but is herein shown, for illustrative purposes, as applied to the peerless eyeleting machine disclosed in United States Patent No. 933,315, issued September 7, 1909, to William F. Lautenschlager.

In the machine of said patent, the work, a shoe upper, is fed step by step to the lower setting die, the length of the feed step being controlled by the movement of a feed arm which cross-reciprocates a punch head carrying the combined punch and upper setting die. The feed takes place while the punch is in the work. The length of feed is regulated by varying the effective stroke of the feed arm through a pin plate having a plurality of holes, any one of which may receive a controlling pin, the position of which in the plate determines, through suitable connecting mechanism, the amplitude of movement of the feed arm. The requisite length of feed for any particular size or style of shoe is determined by the skill of the operator in selecting the proper hole in which to place the controlling pin.

The object of the present invention is to eliminate the judgment of the operator in determining the spacing required for the proper insertion of eyelets, or other fasteners, in different sizes and styles of shoes, or in other work where a variation in spacing is essential.

In accordance with this object, a feature of the invention comprises a fastener spacing attachment, for machines of the character indicated, which can be set by the operator according to instructions previously worked out, making it necessary for the operator merely to follow certain definite and very simple directions when changing from one required spacing to another. To this end, a simple form of pin plate is provided with which there is employed one of a number of interchangeable templets so designed as to render ineffective all of the pin holes except those required in spacing fasteners for the different sizes of the style of shoe for which the templet was made. Each templet bears a symbol corresponding to the symbol

on the tag of a rack or case of shoes. Consequently, the operator need only select from the templets that one of the same symbol as that on the tag of any case of shoes to be operated upon, secure this templet to the pin plate, and then proceed with her work, using for the various sizes the pin holes which the templet leaves uncovered. The designs of the templets provide for the proper location of the first and last fastener relative to the ends of the work and for the fine gradations in spacing required by variation in size, without requiring the operator to punch several shoe uppers, with varying adjustments, before the proper adjustment is determined. The use of the present invention insures uniformity of work, perfects the shoe making, and saves the time of the operator.

To the accomplishment of this object and such others as may hereinafter appear as will readily be understood by those skilled in the art, the invention comprises the features and combinations of parts hereinafter described and then particularly pointed out in the appended claims.

The various features of the invention will be best understood from a description of the preferred embodiment thereof illustrated in the accompanying drawings, in which;

Fig. 1 is a front elevation of the eyeleting machine disclosed in said patent to Lautenschlager showing the novel eyelet spacing mechanism with a templet in place; Fig. 2 is an elevation of a part of the spacing mechanism, without a templet, detached from the machine; Fig. 3 is an end elevation of the spacing mechanism, as shown in Fig. 2, detached from the machine and partly in section; Figs. 4 and 5 are details, in section, on the lines 4-4 and 5-5 respectively of Fig. 2 showing the mode of attaching a templet to the pin plate; and Figs. 6 and 7 are a front and an end elevation respectively of one of the templets.

In the embodiment of the invention illustrated in the drawings, the eyelets are set between a combined upper die and punch 10 on a ram 12 and a lower die 14 on a ram 16. These rams are given vertical reciprocating motion from mechanism actuated by a cam shaft 18, the lower ram through a crank pin 20 and the upper ram through a crank pin 22, which mechanism is like that illustrated and described in said patent to

100

105

110

Lautenschlager. The upper die and punch are mounted upon a head 24 which reciprocates in the line of feed on guides 26 and 28, the mechanism employed being like that described in said patent, actuated from the cam shaft 18. The operation of setting an eyelet is like that described in said patent, namely, the upper die first descends upon the work placed on the anvil 30 and punches a hole, then the reciprocating head 24 moves to the left bringing the punched hole in position to receive an eyelet therein, and finally both rams 12 and 16 are reciprocated in guideways within the head and frame to set 15 the eyelet. The same train of mechanism as is described in said patent is employed to vary the spacing of the eyelets, this train running from the actuator on the cam shaft 18 and including a bell crank lever pivoted 20 at 32 on the frame and having a horizontal arm 34 which corresponds to the arm "67" of the bell crank "56" described in said patent.

The novel mechanism for controlling the spacing of the eyelets, through the train of mechanism just referred to, will now be described. Attached to the machine frame at the rear of the lever arm is a horizontally projecting bracket 36 comprising a vertical plate to the rear side of which there is attached an inverted T-shaped plate, by means of the bolts and pins shown in Figs. 1 and 3, extending through its vertical arm 38. At the upper end of the vertical arm 38 is a bearing for a horizontal pin 40 projecting from one end of a crank arm 42, at the front face of the arm. The other end of the crank arm is connected by means of a vertical link 44 with the outer end of the lever 34. This link is pivoted to the crank arm at its upper 48 end and is connected to the lever 34 by being pivoted to a collar 46 secured to the end of the lever. The pin 40, at the rear face of the vertical arm 38, has a spacing member 48 mounted thereon, and a depending rod 50 is secured thereto comprising a thin flexible strip, the lower end of which terminates in a handle 52. This handle is hollow and receives within it a lever 54 pivoted at its lower end upon a transverse pin 56, said lever terminating at its upper end in a pointer 58 which projects over the front face of the horizontal arm 39 of the inverted T-shaped plate. A coiled spring 60, as shown in Fig. 3, operates to continually maintain 55 the pointer 58 in contact with the front face of the plate arm 39. The rear side of the handle 52 is provided with an inwardly projecting pin 62, opposite the pointer, adapted to enter any one of a plurality of pin holes 64 in the horizontal arm 39 formed on an arc struck from the axis of the pin 40 as a centre.

It will be observed that the pin 62 may be withdrawn from whatever pin hole it may be engaged with by springing the flexible rod

50 backward and while the pin is thus disengaged, the handle may be moved to shift the pointer 58 along the lower edge of the horizontal arm 39 which is of arcuate form and parallel to the row of pin holes 64. 70 The shifting of the handle enables the pointer to be brought into position opposite any one of a series of letters and numbers 66 on the face of the vertical arm 38 just above the pin holes, and the pin 62 is then seated in the corresponding pin hole 64, thus locking it in adjusted position. There is a sufficient number of pin holes and a sufficient number of indications to take care of the entire range of styles and the sizes thereof 80 of the work to be operated upon by the machine. When the handle 52 is shifted from one position to another over the series of pin holes, the rod 50 is moved angularly and this in turn rotates the crank arm 42 which moves the lever 34 and, through the connecting train of mechanism described in said patent, changes the amplitude of the cross-reciprocation of the head 24 and hence varies the spacing between the eyelets to 90 be set.

In order that it will be unnecessary for the operator to use any judgment whatever in selecting the proper adjustment of the spacing mechanism for any particular style of work or a size thereof, means is provided for rendering ineffective all of the pin holes except those which should be used by the operator for the various sizes of the particular style of work which is in hand. To this end, a number of interchangeable templets 68 are provided which have generally the shape of the horizontal arm 39 of the T-shaped plate. A description of one will suffice for all. The templet 68 (Figs. 6 and 7) is provided with a flange 70 at either end of its upper edge, for resting on the upper edge of the pin plate 39 when it is positioned at the back thereof, with a space therebetween for receiving the vertical arm 38. The templet shown in Fig. 6 represents one of the series of interchangeable templets to be used in spacing all the sizes for a single style. Accordingly this templet is provided with only that series of holes 72, selected from the complete series of holes 64, which will give the proper variations in spacing of the eyelets for all the sizes of the style for which the templet is marked. When any one of these interchangeable templets is secured to the back of the pin plate, as shown in Figs. 1 and 3, the holes 72 register with the corresponding holes 64 and the pin 62 of the handle 52 can be seated only in those pin holes which correspond to the holes formed in the templet since all the other pin holes are covered and thereby blocked off or rendered unavailable. The holes or cut-out portions in the templet usually render available holes in the pin plate which are inter- 130

spersed among the entire set of holes in the plate, so that the positions in which the pin 62 may be adjusted are separated by one or more intervening positions of adjustment 5 which are obstructed by the templet. In order to secure the templet in its operative position it is provided in one end with a horizontal slot 74 so that this end can be slipped under a headed pin 76, Fig. 4, which 10 projects from the back of the pin plate 39 at one end thereof. A hole 78 is formed in the opposite end of the templet to register with a hole 80 in the other end of the pin plate. The forward side of the pin plate 15 adjacent the hole 80 is provided with a projecting housing 82 within which slides a push pin 84 projecting through the rear face of the pin plate and having at its rear end an offset head 86 carrying a forwardly projecting pin 88. When the head 86 is rotated into engagement with a stop pin 89 on the pin plate, the pin 88 is then in alignment with the holes 78 and 80. A coil spring 90 surrounding the pin 84 within the housing 20 82, as shown in Fig. 5, normally maintains the pin 88 in a position of engagement with the hole 80. In order to remove the templet 68 from the pin plate, the pin 84 is depressed, thus removing the pin 88 from the 25 holes 78 and 80 and is then rotated to turn its head 86 down against a stop pin 92 where it is clear of the end of the templet. The templet may then be removed, to permit substitution of another, by withdrawing its 30 opposite end from beneath the pin 76.

It will be understood that there are a sufficient number of interchangeable templets, each marked with a symbol, as shown in Fig. 40 6, which together correspond to all the symbols used on the case tags to indicate the various styles of shoes that are to be operated upon. Consequently when a new case of shoes is brought to the operator, she inspects the tag, selects the templet having the same 45 symbol as that on the tag, places the templet in position on the pin plate, and then proceeds with her work. She knows that all the pin holes are covered except those for properly spacing fasteners for the sizes 50 of the style in hand, that the open hole farthest to the left is for the smallest size, and that the open hole at the other end is for the largest size. The shoe uppers are taken in regular order as to size, and for perfect 55 spacing it is merely necessary that the controlling handle be moved over the space of one hole, starting at one end, for each new size. The openings in the templets are so selected, for the style indicated by the symbol thereon, that the spacing adjustment locates the first and last fasteners at the proper 60 distance from the bottom and top of the work for all sizes of that particular style. It is, therefore, unnecessary when using the 65 present invention for the operator to make

any trial adjustments of the spacing mechanism since by its use all the determinations formerly left to the judgment and skill of the operator are eliminated. Usually a given order includes only a comparatively 70 small number of sizes of a certain style so that only a very few positions of the adjusting arm need be provided for on a single templet. In fact this number obviously can be reduced, so far as may be deemed advisable, by increasing the number of templets 75 employed and using suitable symbols.

The nature and scope of the invention having been indicated and the preferred embodiment of the invention having been specifically described, what is claimed as new, is:—

1. In a fastener inserting machine of the type in which the fasteners are set successively in spaced relation and mechanism is provided to vary the spacing controlled by 80 the position of an adjustable arm, a pin plate having a series of pin-receiving holes indicating the required position of the arm for the correct spacing of all the different styles and the sizes thereof of the work to 85 be operated upon over which the arm is moved, a pin on the arm for entering said holes one at a time to adjust the spacing mechanism in position for the spacing indicated thereby, a templet having a series of 90 pin holes indicating the required position of the arm for the different sizes of a single style, and means for securing said templet to the pin plate with its holes registering with the corresponding holes in the pin plate 95 100 and closing other holes interspersed with said registering holes.

2. In an eyelet setting machine having mechanism for adjusting the spacing of the eyelets in the work, said mechanism including an adjustable device for determining the spacing, the combination of a plate over which said device is adjustable, means for holding said device in any desired position of adjustment, a templet for limiting the 110 positions in which said device may be held to those positions required for certain pre-selected work, certain of the latter positions being separated from each other by one or more intervening positions of adjustment 115 which said templet renders unavailable, and means for holding said templet in its operative relationship to said plate and said device, but permitting the removal of the templet and the substitution therefor of another 120 templet.

3. In an eyelet setting machine of the type in which the eyelets are set consecutively in spaced relationship and mechanism is provided to vary the spacing, said mechanism 125 being controlled by an adjustable arm, means cooperating with said arm to hold it in any one of a series of positions of adjustment, and a templet for limiting the positions in which said arm may be held to those posi- 130

tions required for certain preselected work, certain of the latter positions being separated from each other by intervening positions of adjustment which said templet renders unavailable.

4. In an eyelet setting machine having an arm adjustable to vary the spacing of the eyelets, a pin plate provided with holes to cooperate with said arm to hold it in its 10 different positions of adjustment, a templet arranged to expose certain of said holes, but leaving others, interspersed with those so exposed, unavailable for cooperation with the arm, and means for holding said templet in its operative relationship to said plate, but permitting the removal of the templet.

5. In an eyelet setting machine of the type in which the eyelets are set consecutively in 20 spaced relationship and mechanism is provided to vary the spacing, said mechanism being controlled by an adjustable arm, a plate over which said arm is adjustable, said plate having a series of pin receiving holes 25 indicating the required positions of the arm for the correct spacing of all the different styles and sizes of the work to be operated upon, a pin carried by said arm for entering any of said holes to hold said arm in any 30 individual position of adjustment, and a templet removably mounted on said plate and permitting the entrance of said pin into only selected holes which indicate the spacing for certain preselected work, certain of 35 the holes so selected being located relatively remote from each other, and said templet blocking intervening holes.

6. In a fastener inserting machine having 40 mechanism for adjusting the spacing of the fasteners in the work, said mechanism in-

cluding an adjustable device for determining said spacing, the combination of means for holding said device in any one of a series of positions of adjustment, a templet for limiting the positions in which said device may be held to those positions required for certain pre-selected work, certain of the latter positions being separated from each other by one or more intervening positions of adjustment which said templet obstructs, and means for removably holding said templet in its operative position.

7. A fastener inserting machine having, in combination, setting dies, one of which is movable to engage and feed the work step by step, actuating mechanism for said dies, means connected with said actuating mechanism for varying the length of feed, said means including an adjustable controlling arm, means for holding said arm in any one of a series of positions of adjustment whereby the feed spacings required for all styles and sizes of work to be operated upon may be obtained, a templet arranged to prevent the adjustment of said arm in certain of 65 said positions but leaving other positions interspersed in said series available for adjustment, and means for removably holding said templet in its operative position.

8. An eyelet setting machine having in 70 combination a pin plate and a templet, comprising a plate constructed to cover a portion of said pin plate and arranged to be removably secured to said pin plate, said templet having cut out portions to expose 75 certain holes in said pin plate while obstructing other holes interspersed with those so exposed.

LUMAN HOLDEN.
